COMBINATION SHAVING MUG AND
SOAP PROTECTOR

James V. Amendola, Kenosha, Wis.

Application December 12, 1952, Serial No. 325,687

2 Claims. (Cl. 45—136)

1

This invention relates to a soap protector and more particularly to bar soaps such as used in conjunction with a shaving mug, and it consists in the constructions, arrangements and combinations herein described and claimed.

It is well known that shaving mugs which house a bar or cake of soap for shaving purposes permit water to pass between the soap and the wall of the mug with consequent waste of soap due to retention of water within the mug, even though attempts may be made to discharge the water by inverting the shaving mug.

It is therefore the principal object of the invention to provide a bar or cake of soap constructed to space the soap from the vertical wall of a shaving mug permitting drainage of water therefrom upon inversion of the shaving mug.

More specifically, it is an object of the invention to provide a means for embracing a bar of soap, said means being adjustable longitudinally of the soap and including radially projecting means adapted to engage the wall of a shaving mug to hold the soap in spaced relation with respect to the wall of the mug, thus permitting ready removal of water from the mug after completion of the lathering operation, thus conserving the soap, as well as permitting aeration of the soap due to circulation of air around the soap.

Additional objects, advantages and features of invention will be apparent from the following description, considered in conjunction with the accompanying drawing, wherein,

Figure 1 is a fragmentary perspective view of a shaving mug housing a bar of soap, the latter having my invention applied thereto.

Figure 2 is a top plan view thereof, and

Figure 3 is a top plan view of my spacing means.

There is illustrated a shaving mug 10 of conventional construction including a bottom wall 11 and a circumscribing upright wall 12.

A bar or cake of soap 13 of a diameter less than the interior of the mug is shown within the mug and circumscribing the soap 13 is an annular ring 14 of a diameter to permit longitudinal adjustment thereof upon the soap to elevate or lower the soap within the shaving mug. The ring 14 may be formed from any suitable strap

metal or it may be constructed from plastic materials, but in any event the ring is formed with radially extended lugs 15, equally spaced apart and of such lengths as to frictionally engage the interior wall of the mug to secure the soap in a central position and spaced from the wall 15 of the mug.

It will be understood that the bar or cake of soap may have the lugs 15 formed as an integral part thereof and serve the same purpose.

In operation, it will be seen that when a shaving brush is employed to develop a lather excess water will be accommodated in the space 16 and upon inversion of the mug such water will readily drain from the mug and due to the fact that air may circulate about the soap it will be readily dried and waste of soap is thus prevented.

While I have shown and described a preferred form of the device this is by way of illustration only, and I consider as my own all such modifications in construction as fairly fall within the scope of the appended claims.

I claim:

1. The combination of a shaving mug and a bar of soap, said bar of soap having a ring thereon, said ring being longitudinally adjustable on said bar of soap, said ring having radially extended lugs adapted to contact the interior vertical wall of said mug and maintain said soap in spaced relation with respect to said wall.
2. A bar of soap adapted to be positioned within a shaving mug, said bar of soap having a ring thereon, said ring being longitudinally adjustable thereon and having radially extended and circumferentially spaced lugs adapted to contact the interior vertical wall of the shaving mug when positioned therein and maintain said soap in spaced relation with respect to said wall.
